UNITED STATES PATENT OFFICE

2,421,341

PLAY CRIB

Edward A. Lynch, Merion, Pa.

Application January 16, 1945, Serial No. 573,015

7 Claims. (Cl. 5—93)

1

This invention relates to a child's crib and has for an important object thereof, the provision, in a device of this character, of an arrangement for permitting the crib to be utilized both as a crib and play pen.

A further object of the invention is the provision of a flooring for use in the crib which may be permanently connected in the crib structure and which, when not in use, may be conveniently stored away in the confines of the crib.

A further object of the invention is the provision in a structure of this character of an arrangement such that the flooring may be disposed against one of the crib sides, if desired, to act as a means for checking drafts or for shielding the occupant from light or the sun.

These and other objects I attain by the construction shown in the accompanying drawings, wherein for the purpose of illustration, I have shown a preferred embodiment of my invention and wherein:

Fig. 1 is a plan view of a crib constructed in accordance with my invention, the play pen bottom being disposed in its inoperative position;

Fig. 2 is a side elevation thereof;

Fig. 3 is a section taken on the line 3—3 of Fig. 2;

Fig. 4 is a view similar to that of Fig. 3 but illustrating the flooring in operative position;

Fig. 5 is a section on line 5—5 of Fig. 4, the flooring being illustrated in solid lines in one of its operative positions and in dotted lines in a second operative position;

Fig. 6 is a fragmentary section similar to that of Fig. 4 showing the flooring in use as a light, sun, or draft shield; and

Fig. 7 is an enlarged detailed view illustrating the construction of the mounting means for the flooring.

Referring now more particularly to the drawings, the crib frame comprises end members 10, side members 11 and 12 and a spring frame 13. One of the side members 12 is preferably of the vertically shiftable type being mounted on vertical guide rods 14 to this end.

In accordance with my invention, the spring frame 13 is made slightly narrower than the distance between the side members 11 and 12 and is offset to that side of the crib bearing the stationary side member 11, thus providing a space 15 between the spring frame and the slideable side member 12. To the end members 10, a second set of vertical guide members 16 are connected and upon these guide members sleeves 17 are vertically shiftable. Pivoted to the sleeve 55

2

17 through arms 18 is a panel 19 formed in two sections hinged at 19a.

These sections may be folded flatly against one another as shown in Figs. 1, 2, and 3, and when so arranged, the flooring may be slid into the space 15 and will be at this time supported in a lowered position by engagement of the sleeve 17 with the brackets 20 connecting the lower ends of the guides 14 and 16 to the crib ends. In this position the crib will function in its usual manner without interference from the flooring. When it is desired to employ the flooring, it is slid upwardly until detents 21 carried by the sleeve 17 engage in notches 22 in the guides 16 following which it may be placed flatly upon the mattress 23 of the crib. When it is desired to employ the flooring as a light, sun, or draft shield, the panel is elevated in the same manner, but the sections are placed in alignment vertically at which time spring catches 24 may be engaged with the guides 14 to hold it in its vertical position.

Since the structure illustrated is obviously capable of considerable modification without departing from the spirit of the invention, I do not wish to be understood as limiting myself thereto except as hereinafter claimed.

I claim:

1. In a crib, a frame comprising end and side members and a spring frame mounted in said frame with one side thereof spaced from the adjacent side member, a panel, means slidably and pivotally connecting said panel to the frame for movement from a lowered inoperative position where it is disposed in the space between the spring frame and side member to an operative position where it may be disposed over the spring frame as a flooring for the crib.

2. In a crib, a frame comprising end and side members and a spring frame mounted in said frame with one side thereof spaced from the adjacent side member, a panel, means slidably and pivotally connecting said panel to the frame for movement from a lowered inoperative position where it is disposed in the space between the spring frame and side member to an operative position where it may be disposed over the spring frame as a flooring for the crib or in parallel relation to the adjacent side, and means to secure said panel in the last-named position.

3. In a crib, a frame comprising end and side members and a spring frame mounted in said frame with one side thereof spaced from the adjacent side member to provide a vertical space 55 between said side member and said spring frame,

and a panel means slidably connecting the frame and panel for movement from an inoperative position where it is disposed in said space to an operative position where it is disposed above the spring frame and in parallel with the adjacent side member, and means to secure the panel in its operative position.

4. In a crib, a frame comprising end members, side members, and a spring frame connecting the end members and disposed to provide a vertical space between it and one of the side members, a vertical guide secured to each end member adjacent said side member, sleeves slidable on said guides and a panel hinged to said sleeves for movement into horizontal or vertical positions and disposable in said space when in vertical position.

5. In a crib, a frame comprising end members, side members, and a spring frame connecting the end members and disposed to provide a vertical space between it and one of the side members, a vertical guide secured to each end member adjacent said side member, sleeves slidable on said guides and a panel hinged to said sleeves for movement into horizontal or vertical positions and disposable in said space when in vertical position, said panel being formed in two longitudinally hinged sections foldable to lie in face to face relation.

6. In a crib, a frame comprising end members, side members, and a spring frame connecting the end members and disposed to provide a vertical space between it and one of the side members, a vertical guide secured to each end member adjacent said side member, sleeves slidable on said guides and a panel hinged to said sleeves for

movement into horizontal or vertical positions and disposable in said space when in vertical position, and means to support said sleeves in either of two vertically spaced positions.

5. In a crib, a frame comprising end members, side members, and a spring frame connecting the end members and disposed to provide a vertical space between it and one of the side members, a vertical guide secured to each end member adjacent said side member, sleeves slidable on said guides and a panel hinged to said sleeves for movement into horizontal or vertical positions and disposable in said space when in vertical position, means to support said sleeves in either of two vertically spaced positions, said panel being formed in two longitudinally hinged sections foldable to lie in face to face relation.

EDWARD A. LYNCH.
